FRANCIS L. PRUYN, OF NEW YORK, N. Y., ASSIGNOR TO THE UNDERPINNING & FOUNDATION COMPANY, OF NEW YORK, N. Y.

TUBE JOINT AND GUIDE.

1,188,485.

Specification of Letters Patent. Patented June 27, 1916.

Application filed September 3, 1910. Serial No. 580,356.

To all whom it may concern:

Be it known that I, FRANCIS L. PRUYN, a citizen of the United States, and a resident of the city of New York, county of New York, and State of New York, have invented certain new and useful Improvements in Tube Joints and Guides, of which the following is a full, clear, and exact specification, such as will enable others skilled in the art to which it appertains to make and use the same.

This invention relates to joints for tubes such as are ordinarily used in the making of foundations for buildings, and particularly where such foundations require going to considerable depth to secure a firm footing, to do which it is now a common practice to drive into the ground metal tubes of greater or less diameter. These tubes are driven in sections, by means of a steam hammer or other suitable driving mechanism. When one section of tube has been driven, a second section is placed in position over the first and both are then driven, these being followed by other sections until the required depth is attained. When a sufficient number of sections have been driven, the earth contained within the tube is removed and concrete placed therein, which, when it sets, forms a solid concrete pile, the tube acting as a mold for the concrete.

In the driving of the tube sections, it is desirable to have some means of quickly and accurately positioning the adjacent tube ends with respect to each other, and retaining the same in place, so as to keep the tubes in proper alinement and at the same time form a strong and fluid-tight connection between the sections, with the exterior surfaces, at the point of connection, as even and smooth as possible, for it will be evident that any material projection of metal outwardly at the tube joints will be likely to interfere with the driving operation. As the tubes ordinarily used for this work are of comparatively cheap manufacture, the abutting ends are not always finished in such manner as to afford uniform flat driving surfaces, and consequently there is often present the danger of one section not properly driving the section preceding it, for the reason that the end of one section may overlap or drive out of shape the adjacent end of the other section, in which

case difficulty results and the work is impeded.

The object of my invention, therefore, is to provide a combined joint and guide for such tubes, which will facilitate properly placing and retaining in position the tube sections, which will make a close joint with the tube ends, and which will afford a uniform driving surface for the abutting ends of the tube sections.

Other objects, such as economy of manufacture, and ease and accuracy in the application of the device, will readily suggest themselves from a reading of the specification, in connection with the accompanying drawings, in which—

Figure 1 is a view partly in section and partly in elevation, with portions broken away; and Fig. 2 is an elevation.

Referring to the construction illustrated in the drawings, A and B represent, respectively, two tube sections such as I have referred to above, the adjacent ends of which are designated at A', B'.

C represents my combined tube joint and guide applied thereto.

The tube joint C comprises a relatively short tube or bushing D, portions of which are adapted to fit tightly within the ends of the tube sections A, B. The tube joint C is formed of metal, and, preferably cast integral therewith (or formed separately and secured thereto), approximately midway thereof, is an outwardly projecting lug or flange E, which I prefer to extend entirely around the bushing D. The lug or flange E projects laterally from the outer surface of the bushing D a space approximately the thickness of the tube sections, so that when the parts are in position, as shown in Fig. 1, the outer face of the lug E will lie flush with the outer surface of the tube sections. Preferably the upper and lower faces of the lug E are beveled inwardly, as indicated in Fig. 1, in order to confine the ends of the tube-sections A' and B'. The ends of the bushing D are made slightly tapering, as shown at D', D'', so that the same may be easily and quickly inserted within the end portions of the tubes preliminary to being driven into place.

The application and function of the device will be readily apparent from the foregoing description. Assuming that the tube section A has been driven into the ground to

nearly its full length, the lower end of the bushing D is inserted within the end of said tube section, the tapering end D' permitting of its ready insertion notwithstanding any slight variations in the thickness of the tube A. The hammer then drives the bushing D into place within the tube A until the lower side of the lug E rests upon, or nearly upon, the end A' of the tube section A. 5 Thereupon, the end of the tube section B is placed over the tapering end D' of the bushing D, and the next blow of the hammer forces the adjacent ends of the tube sections securely in place against the upper and lower faces of the lug or flange E. 10 15 It will be observed that there is afforded by the upper and lower surfaces of the flange E driving faces of uniform width, whereby all danger of the tubes telescoping 20 and getting out of alignment thereby is avoided, and the bushing D acts as an interior guide in driving the tube sections true. Furthermore, due to the slightly tapering ends, a larger bushing can be readily inserted and a more tightly fitting joint made 25 in the driving operation than would otherwise be possible. It will also be observed that the beveled faces of the flange E serve to confine the edges of the ends of the tube sections and prevent their spreading during 30 the driving operation.

While I have here shown and described one embodiment and application of my invention, I wish it to be understood that I 35 do not confine myself to the precise details herein set forth, as modification and variation may be made without departing from the spirit of the invention as defined by the appended claims.

40 What I claim is:

1. In incased concrete piling, the interiorly fitting alining sleeve for joining the abutting ends of the metallic casing sections together, provided with a medial collar, the

opposite faces of which collar in section diverge in unbroken lines from the outside of the sleeve to the outside of the collar, to fit between and yet tend to press inwardly the abutting ends of the casing sections and to form stops for the sleeve and abutments for the ends of the casing sections. 45 50

2. In incased concrete piling, the combination, with two superposed metallic casing sections of the same radial thickness throughout, of a metallic alining sleeve having its ends fitted within the casing sections and provided with an exterior medial collar, the opposite faces of which collar in section diverge in unbroken lines from the outside of the sleeve to the outside of the collar, and fit between and tend to press inwardly the 55 60 abutting ends of the casing sections.

3. The interiorly fitting alining sleeve for joining the abutting ends of the metallic casing sections together, provided with a medial collar, the opposite faces of which collar in section diverge in unbroken lines from the outside of the sleeve to the outside of the collar, to fit between and yet tend to press inwardly the abutting ends of the 70 casing sections and to form stops for the sleeve and abutments for the ends of the casing sections. 65

4. The combination with two superposed metallic casing sections of the same radial thickness throughout, of a metallic alining sleeve having its ends fitted within the casing sections and provided with an exterior medial collar, the opposite faces of which collar in section diverge in unbroken lines 75 80 from the outside of the sleeve to the outside of the collar, and fit between and tend to press inwardly the abutting ends of the casing sections.
